CLAIM

The ornamental design for a laparotomy sponge container, as substantially shown and described.

DESCRIPTION

FIG. 1 is an isometric view of the laparotomy sponge container showing my new design;
FIG. 2 is a top plan view thereof;
FIG. 3 is a front view thereof;
FIG. 4 is a left side view thereof;
FIG. 5 is a right side view thereof; and
FIG. 6 is a bottom plan view thereof.
